JOHN V. MOORE AND CARL JENISCH, OF PAWTUCKET, RHODE ISLAND, ASSIGNEES TO
MOORE FABRIC COMPANY, OF PAWTUCKET, RHODE ISLAND, A CORPORATION OF
RHODE ISLAND

MACHINE FOR WINDING CONE WARPS

Application filed November 15, 1930. Serial No. 495,952.

This invention relates to a machine for winding warp threads on a tapered warp beam and relates more particularly to the winding of a warp composed in whole or in part of elastic warp threads.

It is the general object of our invention to provide a machine by which elastic warp threads may be fed under slight but substantially uniform tension to a conical tapered warp beam.

A further object of the invention relates to the provision of improved means for storing the warp threads which are to be fed to the machine, and to the provision of improved means for delivering the threads to the conical warp beam at different but definitely related speeds.

Our invention further relates to arrangements and combinations of parts which will be hereinafter described and more particularly pointed out in the appended claims.

A preferred form of the invention is shown in the drawings, in which

Fig. 1 is a sectional side elevation of our improved machine;

Fig. 2 is a side elevation of certain driving connections;

Fig. 3 is a plan view of the machine on enlarged scale;

Fig. 4 is a detail sectional side elevation, looking in the direction of the arrow 4 in Fig. 3;

Fig. 5 is a detail plan view, looking in the direction of the arrow 5 in Fig. 4, and

Fig. 6 is a detail sectional view of one of the thread-gripping discs.

Referring to the drawings, we have shown a winding machine having a frame 10 in which a driving shaft 11 is rotatably mounted. The shaft 11 is provided at one end with a handle 12 by which it may be rotated and at the opposite end with a dog 13 having a driving pin 14 engaging a recess in one of the heads of a tapered warp beam 15.

The opposite head of the warp beam similarly engages a dog 16 on a shaft 17 which is rotatable in bearings in the frame 10 and is mounted in line with the shaft 11.

The beam 15 has a shaft or gudgeon 20, the

ends of which are received in axial openings in the dogs 13 and 16.

A feed-roll shaft 22 is mounted in fixed bearings and supports a tapered feed-roll 24, shown in the drawings as formed in three tapered sections. The ratio between the largest and smallest diameters of the three-part feed-roll 24 is substantially the same as the ratio of the largest and smallest diameters of the warp beam 15.

The warp beam shaft 17 is connected to the feed-roll shaft 22 by sprockets 27 and 28 and a chain 29 (Fig. 2). The surface speed of the feed-roll and of the warp beam barrel are substantially the same.

Presser rolls 30 are rotatably mounted in swinging arms 31 and engage the upper surfaces of the sectional feed-roll 24, and these presser rolls 30 are also preferably of a corresponding taper.

The warp threads W are preferably stored in open-top receptacles 40, as shown in Fig. 1, and are drawn upward therefrom around guide rods 41 located substantially above the receptacles 40. The warp threads W then pass downward around a guide rod 42 and upward around a second guide rod 43 and through a comb 44.

The threads W are drawn from the receptacles 40 by thread-gripping and forwarding members 50 (Figs. 4 and 5) by which the threads are delivered to the sectional feed-roll 24.

Each thread-gripping member 50 is preferably formed as indicated in Fig. 6 and comprises a pair of plates 52, mounted face to face on a hub 53, and each having a plurality of peripheral fingers 54. The fingers 54 of each plate 52 are bent and displaced toward and beyond the face of the adjacent plate 52, thus giving them the overlapping relation shown in Fig. 6.

The fingers 54 thus provide a V-shaped peripheral groove, adapted to freely engage an elastic warp thread and to grip and draw forward the thread at a predetermined speed.

A series of these gripping and forwarding members 50 are mounted on a shaft 60, rotatable in fixed bearings 61 (Fig. 1) and provided with a sprocket 62 (Fig. 2) con-

nected by a chain 63 to a sprocket on the shaft 22 previously described. These sprockets are so proportioned that the peripheral speed of the members 50 at their thread gripping surfaces is substantially the same as the peripheral speed of the associated part of the feed-roll 24. The several members 50 progressively decrease in diameter from one end of the set to the other so as to maintain 10 the same ratio of feeds throughout the width of the warp.

Additional combs 65 and 66 (Fig. 3) are provided for guiding the threads W from the feed-roll 24 to the warp beam 15.

15 While we have indicated a handle 12 for turning the warp beam 15 and other connected parts, it will be understood that any suitable power drive may be substituted.

Having described the construction of our 20 improved winding machine, the operation and advantages thereof are as follows:

The warp threads W are drawn by the 25 forwarding members 50 against the uniform but slight friction of the guide bars 41, 42 and 43 and this is the only tension placed on the warp threads as they are withdrawn from the containers 40 in which they are loosely coiled. The tension of the threads is thus much more uniform than in a construction 30 in which the threads are drawn from spools in a reel, in which case the size and weight of the spools, as well as the inertia thereof, causes wide variations in thread tension.

35 The warp threads W are forwarded from the members 50 to the feed-roll 24 at speeds corresponding in ratio to the diameter of the feed-roll at the points to which the respective threads are delivered, and the 40 threads are forwarded at the same rate and in the same speed ratio to the warp beam 15.

We are thus able to wind a tapered cone 45 warp from elastic warp threads in such a manner that all of the warp threads are under substantially the same tension at the point of delivery to the warp beam.

As the amount of warp on the warp beam 50 increases, a slight increase in peripheral speed at the surface of the beam will be produced, causing a slightly increased tension on the warp as a whole, but this increase of tension is relatively slight, due to the definitely limited length of a rubber warp. Furthermore, such variations in total warp 55 tension are not objectionable, so long as the tension in the different warp threads is maintained uniform throughout the width of the warp.

In other words, the important thing in 60 winding a conical warp beam with elastic warp threads is to maintain a substantially uniform tension of all of the warp threads as compared with each other at any given point in the warp. Variations in total warp 65 tension are readily taken care of by using an

apron or other suitable surface friction to retard the unwinding of the warp in the loom.

While the machine has advantages for 70 general purposes, it is particularly effective with bare rubber or covered rubber threads, which require very careful and delicate handling to prevent wide variations in thread tension, as between different threads at the same point in the warp.

Having thus described our invention and the advantages thereof, we do not wish to be limited to the details herein disclosed, otherwise than as set forth in the claims, but what we claim is:—

1. In a winding machine, a tapered warp beam, a tapered feed roll, a pressor roll yieldingly engaging said feed roll, a plurality of open containers in which a series of elastic warp threads are loosely and separately coiled, and means to draw said threads from said containers at different relative speeds and to deliver said threads under substantially uniform and positive but slight tension to said feed roll.

2. In a winding machine, a tapered warp beam, a tapered feed roll, a pressor roll yieldingly engaging said feed roll, a shaft rotatable in timed relation to said feed roll and a tapered series of thread-gripping and forwarding members mounted on said shaft and effective to deliver a series of elastic warp threads at different speeds but under substantially uniform and positive but slight tension to said feed roll.

3. In a winding machine, a tapered warp beam, a tapered feed roll, a tapered set of thread-gripping and forwarding members from which the warp threads are delivered under substantially uniform and definite but slight tension to the feed roll, and means to rotate all of said parts in predetermined speed relations.

4. In a winding machine, a thread-gripping member comprising pairs of identical discs reversely secured face to face and having their peripheral portions slotted to form a series of fingers, projecting at one side only of each disc, the fingers of each disc being displaced toward and beyond the adjacent face of the other plate to form a V-shaped thread-receiving groove.

In testimony whereof we have hereunto affixed our signatures.

JOHN V. MOORE.
CARL JENISCH.
